US00D750675S

(12) **United States Design Patent**
Fagerberg et al.

(10) **Patent No.:** **US D750,675 S**
(45) **Date of Patent:** **** Mar. 1, 2016**

(54) **PRESSURE SEALING MEANS FOR CABLE TRANSIT**

(71) Applicants: **Johan Fagerberg**, Karlskrona (SE); **Anders Karlsson**, Fågelmara (SE)

(72) Inventors: **Johan Fagerberg**, Karlskrona (SE); **Anders Karlsson**, Fågelmara (SE)

(73) Assignee: **MCT Brattberg AB**, Karlskrona (SE)

(**) Term: **14 Years**

(21) Appl. No.: **29/508,525**

(22) Filed: **Nov. 7, 2014**

(30) **Foreign Application Priority Data**

May 7, 2014 (EP) 002459057

(51) **LOC (10) Cl.** **15-99**

(52) **U.S. Cl.**

USPC **D15/146**

(58) **Field of Classification Search**

USPC D15/145, 146

(57) **CLAIM**

The ornamental design for a pressure sealing means for cable transit, as shown and described.

DESCRIPTION

FIG. 1 is a first perspective view of the pressure sealing means for cable transit;

FIG. 2 is a second perspective view of the pressure sealing means for cable transit;

FIG. 3 is a front view of the pressure sealing means for cable transit;

FIG. 4 is a rear view of the pressure sealing means for cable transit;

FIG. 5 is a side view of the pressure sealing means for cable transit;

FIG. 6 is a top view of the pressure sealing means for cable transit; and,

FIG. 7 is a bottom view of the pressure sealing means for cable transit.

1 Claim, 7 Drawing Sheets
